CLAIM

The ornamental designs for a credit card-size low-E detection device for positioning of the device against a glass, as shown and described.

DESCRIPTION

FIG. 1 is a perspective front elevational view of a credit card-size low-E detection device for positioning of the device against a glass according to one embodiment; FIG. 2 is a top plan view of the embodiment; FIG. 3 is a back plan view of the embodiment; FIG. 4 is a side elevational of the embodiment; FIG. 5 is an elevational view of the embodiment; and, FIG. 6 is a back perspective view of the embodiment. The broken lines in the Figures are included for the purpose of illustrating portions of the embodiments that form no part of the claimed design.
